UNITED STATES PATENT OFFICE.

ALEXIS DE BISSCHOP, OF PARIS, FRANCE.

IMPROVEMENT IN GAS-ENGINES.

Specification forming part of Letters Patent No. 178,121, dated May 30, 1876; application filed March 14, 1876.

To all whom it may concern:

Be it known that I, ALEXIS DE BISSCHOP, of Paris, France, have invented certain Improvements in Gas-Engines, of which the following is a specification:

My invention relates to that class of motive-power engines which are operated by the explosion of a mixture of air and gas; and the object of my invention is to prevent the condensation of the gases when the engine is first put in operation. This object I attain in the manner which I will now proceed to describe, reference being had to the accompanying drawings, in which—

Figure 1 is a longitudinal vertical section of a gas-engine by which my invention is carried into effect; Fig. 2, a transverse vertical section.

A is the cylinder; B, the piston, and D the piston-rod. To the top of the piston-rod is attached a block, b, which is guided in the standard D', connected to or forming part of the cylinder, and to this block is pivoted one end of a rod, c, connected at the opposite end to the crank e on the shaft of the driving-wheel E. The slide-valve F, for admitting the air and gas to the cylinder A, is operated from the eccentric e' on the shaft of the driving-wheel through the medium of the lever f'. This slide-valve is cut away near the center, as shown in Fig. 2, in order that it may serve to open and close communication between the cylinder and the air and gas passage d. The valve-chamber communicates at its lower end with the exhaust-passage K. The air-valve G, preferably, consists of a simple plate, having a number of perforations closed by flap-valves composed of strips of rubber. A similar valve, G', is arranged in the gas-inlet d', which communicates with the air-inlet d, so that a mixture of the air and gas is effected before they reach the valve-chest. The gas-supply tube g, in the present instance, is of flexible material, and passes between an upright post, h, and a plate, h¹, pivoted at one end to the post, and acted upon at the other by a set-screw, h², by operating which the pressure upon the tube g, and consequently the amount of gas which

passes through the same, may be regulated at pleasure. In one side of the cylinder, a short distance from the bottom, is an opening, x, and opposite this opening is a gas-jet, X, the flame from which is projected into the cylinder A, and serves to ignite the mixture of air and gas admitted to the same.

In engines of this class, as usually constructed, the coolness of the cylinder when the machine is first put in operation causes the condensation of the gases, and consequent injury of the piston.

In order to heat the cylinder of a gas-engine by an economical device, the heating being necessary only at the commencement of the operation of the engine, I arrange below the cylinder a supplementary and much larger burner, Y, which can be put in communication with a suitable gas-pipe, so that a flame may be projected against the bottom of the cylinder, in order to heat the same previous to the machine being put in motion.

The operation of the engine is as follows: The fly-wheel E is first given a few turns, in order to induce the passage of air and gas into the cylinder. This mixture of air and gas will be ignited by the flame from the jet X, and the power generated from the consequent explosion will raise the piston. When the latter commences its downward stroke the valve E will be so operated by the eccentric as to close the inlet-passage d, and open communication between the cylinder and the outlet K. The momentum imparted to the wheel E will be such, however, that it will continue to turn, so as to raise the piston slightly, and open the valve F for the admission of another supply of air and gas, the explosion of which again raises the piston. These successive explosions will continue to rotate the driving-wheel at a comparatively uniform speed.

It will be evident that as soon as the cylinder of the engine becomes once sufficiently heated by the gas-jet from the burner Y, communication with the supply-pipe may be closed, thus obtaining an economy in the consumption of gas, as well as economy in the construction of the device.

I claim as my invention—

The method described of preventing condensation of the gases in an air and gas engine—that is to say, heating the cylinder by means of a gas-jet beneath the latter, preparatory to injecting the explosive mixture, substantially as set forth.

In testimony whereof I have signed my name to this specification in the presence of two subscribing witnesses.

ALEXIS DE BISSCHOP.
